UNITED STATES PATENT OFFICE

172,979

COMBINED DIRT CARRYING AND DUMPING BODY

Edward H. Mortag, Milwaukee, Wis., assignor to Koehring Company, Milwaukee, Wis., a corporation

Application June 22, 1953, Serial No. 25,598

Term of patent 14 years

(Cl. D14—3)

To all whom it may concern:

Be it known that I, Edward H. Mortag, a citizen of the United States, residing at 3026 W. Concordia Avenue, Milwaukee, in the county of Milwaukee and State of Wisconsin, have invented a new, original, and ornamental Design for a Combined Dirt Carrying and Dumping Body, of which the following is a specification, reference being had to the accompanying drawing, forming a part hereof, wherein:

Figure 1 is a front perspective view of a combined dirt carrying and dumping body embodying my new design.

I claim:

The ornamental design for a combined dirt carrying and dumping body, substantially as shown.
